Roger Murray Campbell
ATTORNEYS

UNITED STATES PATENT OFFICE.

SAMUEL SMITH, OF BROOKLYN, NEW YORK, ASSIGNOR TO MERGENTHALER LINOTYPE COMPANY, A CORPORATION OF NEW YORK.

SLUG-TRIMMING MECHANISM.

Application filed January 27, 1926. Serial No. 84,059.

My invention relates to typographical casting machines, such as linotype machines of the general organization represented in U. S. Letters Patent No. 436,532, to O. Mergenthaler, wherein type bars or slugs are cast in a mold and then ejected therefrom between two trimming knives, which insure the parallelism of their opposite side faces and the exact thickness required. One of these knives is adjustably mounted in order that the distance between the two may be varied at will to accommodate slugs of different thicknesses. More particularly, it relates to a slug trimming mechanism of the type shown and described in the U. S. patent to D. S. Kennedy, No. 1,002,281, wherein the adjustments of the knife are effected against spring tension by means of a rotary sector plate operated by a hand lever and having a series of transverse, concentrically arranged screw studs, which project different distances from the inner side face thereof and which thus determine the extent of the adjustment desired. In practice, it has been found that after certain adjustments of the sector plate, its hand lever projects so far forwardly of the machine as to stand in the operator's way and to interfere with his free manipulation of the parts. The present invention obviates this difficulty by dispensing with the hand lever altogether, and, moreover, provides means whereby the sector plate may be relieved of spring pressure during its rotary adjustment to avoid excessive wear on the parts.

In the accompanying drawings, I have shown my invention merely in preferred form and by way of example, but obviously many changes and variations may be made therein and in its mode of operation, which will still be comprised within its spirit. Generally speaking, I desire it to be understood that I do not wish to limit myself to any specific form or embodiment, except in so far as such limitations are specified in the claims.

Referring to the drawings:

Fig. 1 is a perspective view of a knife block, equipped with the present improvements; and

Fig. 2 is a central horizontal section thereof.

As best shown in Fig. 2, the adjustable

knife A is fastened by screws *a* to a slide B and arranged opposite to and parallel with the fixed knife A'. For manufacturing reasons, the slide B is made in two sections B', B'', and mounted to move horizontally in a supporting frame C bolted rigidly to the main frame of the machine. In its front face, the section B' is formed with a pair of superposed horizontal grooves or recesses B³ adapted to accommodate spiral springs B⁴, which bear against integral projections *c* on the fixed frame C and urge the slide constantly endwise toward the right to move the knife A away from the opposing knife A'. A rotary sector plate or gauge member D is employed to sustain the knife A in its different adjusted positions, the said member being provided with a series of concentrically disposed screw studs D', which project different distances from the inner face thereof and are arranged to selectively engage a hardened stud B⁵ attached to the adjacent end of the slide B. As a result, the knife A is caused to stand in one position or another, according to the particular screw stud in action. The parts so far described, their construction and mode of operation, except as will be hereinafter pointed out, are or may be substantially the same as those presented in the above-mentioned Kennedy patent.

According to the present invention, it is proposed to relieve the sector plate D of the pressure exerted by the springs B⁴, so that it may be freely rotated in making adjustments. To this end, the knife slide member B is provided with a pin B⁶, which projects forwardly through a slot C' in the frame C and terminates alongside the rear end of a hand lever E, the latter being pivotally mounted on the side of a rigid arm E' located to one side of the sector plate D and out of the way of the operator. With this arrangement, the operation of the lever E, which in the present instance is effected by pressing it toward the arm E', forces the slide B toward the left against the tension of the springs B⁴ to an extent sufficient to locate the stud B⁵ clear of all the studs D' of the sector plate when the latter is rotated and set in another position. After resetting the sector plate, the hand lever E is released to allow the springs to restore the slide B to

the right and bring the stud B^5 into engagement with the newly selected stud D' of the sector plate. Excessive friction between the stud B^5 and the various studs D' , and the 5 wear that would take place as a result, particularly if the studs D' were unhardened, is in this way obviated.

It is important that the sector plate be locked securely in its different adjusted positions, and hence there is employed a flat spring plate F' , which is clamped to the frame C and provided with an actuating handle F^2 . The finger F (see Fig. 2) is supported in a recess C^2 formed in the front 10 arcuate face of the frame C and projects slightly beyond to engage notches D^3 disposed around the inner face of the sector plate D . These notches are arranged diametrically opposite to their respective screw 15 studs D' , so that each notch will always register with the latch finger F when the corresponding stud D' is brought into operative relation to the stud B^5 on the knife slide B . It will also be noted that the handle F^2 is arranged adjacent the arm E' and on the 20 side opposite the hand lever E , so that when the operator grasps the latter to retract the knife slide B , in the manner before stated, the latch F will be disengaged from the active notch D^3 by the same operation. Moreover, the control of the locking device is 25 such that under normal conditions, the knife A' cannot be adjusted without first relieving the sector plate of the pressure exerted by 30 the springs B^4 .

In order to aid the operator in adjusting the knife to produce slugs of different thicknesses and to indicate the adjustments as 35 they are effected, a pointer F^3 is provided, which, in the present instance, is formed on a forward extension of the spring plate F' and arranged flush with the peripheral edge of the rotary sector plate D , the latter being provided (as shown in Fig. 1) with appropriate marks or graduations D^4 .

To adjust the knife, according to the foregoing arrangement, the operator with one hand grasps the lever E and handle F^2 and presses them against the rigid arm E' . By 40 this operation, the sector plate D is unlocked from the frame C and freed of the pressure exerted by the springs B^4 , so that the operator with his other hand may readily turn the sector plate about its fulcrum pin D^2 45 until the mark designating the thickness of the slug desired registers with the pointer F^3 . The two handles E and F^2 are then released to permit the stud B^5 to bank against the selected opposing stud D' and the latch finger F to engage the corresponding notch D^3 . While the sector plate might be rotated 50 directly by hand, owing to the absence of any pressure or strain thereon, it is preferably provided with a turning knob D^5 55 screwed or otherwise fastened thereto.

There is obviously no need of a long hand lever such as was heretofore required.

As before stated, I have shown my invention only by way of example and as applied to a specific style of slug trimming mechanism, but obviously modifications other than the one described will readily suggest themselves to those skilled in the art without departing from the spirit of my invention.

Having thus described my invention, its 75 construction and mode of operation, what I claim and desire to secure by Letters Patent of the United States is as follows:

1. In a slug trimming mechanism, the combination of a knife slide, adjusting means 80 therefor, a spring for maintaining the knife slide in its adjusted positions, means for suppressing the spring, and separate locking means arranged to prevent operation of the knife slide adjusting means before the spring 85 is suppressed.

2. In a slug trimming mechanism, the combination of a knife slide, an adjustable gauge member, means for locking the latter in its 90 adjusted positions, a spring acting to maintain the knife slide in operative engagement with said gauge member, and means controlled by a single operation to unlock the gauge member and relieve it of the spring pressure of the knife slide preparatory to its 95 adjustment.

3. In a slug trimming mechanism, the combination of a knife slide, an adjustable gauge member, means for locking the latter in its 100 adjusted positions, a spring acting to maintain the knife slide in operative engagement with said gauge member, and means for unlocking the gauge member and relieving it of the spring pressure of the knife slide preparatory to adjustment.

4. In a slug trimming mechanism, the combination of a knife slide, a rotary gauge member for locating the slide in its adjusted positions, a spring for holding the slide resiliently against the gauge member, means 110 for locking the gauge member against rotation, and means whereby said member is unlocked and relieved of the spring pressure of the knife slide preparatory to adjustment.

5. In a slug trimming mechanism, the combination of a knife slide, a rotary gauge member for locating said slide in different 115 adjusted positions, a spring acting to maintain the knife slide in operative engagement with the gauge member, a locking latch to hold the gauge member in different rotary 120 positions of adjustment, and two hand levers arranged side by side for simultaneous operation, one connected to the knife slide for moving it away from the gauge member, and the other connected to the locking latch to disengage it from the gauge member.

6. In a slug trimming mechanism, the combination of a knife slide, a single adjustable 125 gauge member provided with a series of lat-

erally projecting studs whose operative faces are arranged stepwise, a spring acting to maintain the knife slide in operative engagement with any selected one of the studs, locking means to prevent the adjustment of the gage member while it is subject to the spring pressure of the knife slide, and means op-

erated in disengaging said locking means to suppress the spring pressure preparatory to the adjustment of the gage member.

10

In testimony whereof, I have affixed my signature hereto.

SAMUEL SMITH.
